DESIGN FOR A KNIFE

Edward K. Madan, Maplewood, N. J.

Application January 23, 1941, Serial No. 98,314

Term of patent 7 years

To all whom it may concern:

Be it known that I, Edward K. Madan, a citizen of the United States of America, residing at Maplewood, in the county of Essex and State of New Jersey, have invented a new, original, and ornamental Design for a Knife, of which the following is a specification, reference being had to the accompanying drawing, forming part thereof.

In the drawing:

I claim:

The ornamental design of a knife, as shown.

EDWARD K. MADAN.
